[57] CLAIM

The ornamental design for an oil candle for insertion into a wine bottle or similar article, as shown and described.

DESCRIPTION

FIG. 1 is a side elevational view of an oil candle for insertion into a wine bottle or similar article showing my new design;

FIG. 2 is a top plan view thereof;

FIG. 3 is an opposite side elevational view thereof on an enlarged scale.

The bottle and flame are shown in broken lines for illustrative purposes only.
